UNITED STATES PATENT OFFICE.

CHARLES KNOTHE, OF NEW YORK, N. Y.

DESIGN FOR A BUCKLE.

SPECIFICATION forming part of Design No. 34,266, dated March 26, 1901.

Application filed February 28, 1901. Serial No. 49,362. Term of patent 3½ years.

To all whom it may concern:

Be it known that I, CHARLES KNOTHE, of New York, in the county of New York and State of New York, have invented and produced a new and original Design for Buckles, of which the following is a specification, reference being had to the accompanying drawings, forming a part of the same.

In the drawings, Figure 1 is a top plan view 10 of a buckle embodying the present design. Fig. 2 is a side elevation.

The leading or characteristic features of the design are the side bars A, having straight diverging faces. A heavy cross-bar B bridges 15 the space between the outer thicker ends of

the side bars, and a thin cross-bar C bridges the space between the inner narrow ends of the side bars A. The opening in the buckle is substantially rectangular, while the contour lines of the buckle-body form a trapezoid. D is a tongue extending from the thin to the thicker cross-bar. 20

I claim—

The design for a buckle as herein shown and described.

CHARLES KNOTHE.
